UNITED STATES PATENT OFFICE.

JESSE W. RENO, OF NEW YORK, N. Y., ASSIGNOR TO OTIS ELEVATOR COMPANY, OF JERSEY CITY, NEW JERSEY, A CORPORATION OF NEW JERSEY.

CONVEYER.

1,178,102.

Specification of Letters Patent.

Patented Apr. 4, 1916.

Application March 10, 1915. Serial No. 13,303.

To all whom it may concern:

Be it known that I, JESSE W. RENO, a citizen of the United States, residing in New York, in the county of New York and State of New York, have invented a new and useful Improvement in Conveyers, of which the following is a specification.

My invention relates to inclined endless conveyers, and has to do with certain improvements in conveyers more particularly of the type covered by a patent granted to me April 10, 1906, and being numbered 817,338.

Essentially the invention consists in certain modifications in construction and arrangement of parts, as will adapt the conveyer for a single chain drive, instead of a two chain drive as shown in the patent above noted, such changes in effect tending toward simplicity and cheapness, and more particularly overcoming certain objectionable features accompanying a two chain drive, which objectionable features will be pointed out fully hereinafter.

In the accompanying drawings, Figure 1 illustrates in longitudinal section, a side view of a conveyer constructed in accordance with my present invention; Fig. 2 illustrates in section, an end view of the upper and return or lower run of the conveyer; Fig. 3 illustrates in plan view, a portion of the conveyer with certain parts removed; and Fig. 4 is a somewhat enlarged plan view of a portion of the driving chain together with certain other parts.

The conveyer comprises a series of steps A, which form an endless movable tread platform connecting different floor levels B and C. The tread surface proper of each step is of the well known type, comprising longitudinal cleats D, which are suitably secured to a suitable horizontal web D', the cleats being so spaced as to produce shallow grooves E therebetween. The usual form of comb landings F are provided at the floor levels, the landings having teeth or prongs adapted to register with the grooves E of the steps.

The front ends D'' of the cleats D extend some distance beyond the front edge of the supporting web, as will be seen from Figs. 1 and 3, and enter vertical grooves or slots G of a riser H, the grooves being produced by the formation of ribs J on the front of the riser web H'.

It will thus far be seen that the cleats D form the tread surface proper of the step, and the front edges of the ribs J form the risers thereof. It will further be seen that the ribs J are in staggered relation with the cleats D forming the tread surface, or in other words the ribs J are in alinement with grooves E, and the forward ends D'' of the tread cleats extend into the grooves G. The purpose of this construction, as is pointed out in the patent heretofore referred to, is to prevent the passenger's foot or apparel from entering and becoming caught between the back edge of one step and the riser of another, especially as the steps are changing their relative positions in passing to or from a landing.

Each step is supported by a pair of inner truck wheels K, and outer truck wheels K', adapted to travel respectively on suitable track rails such as L, L'. The track rails are arranged in a well known manner to form a horizontal run at the landings and an incline run between the landings. The inner truck wheels K are mounted on pins 80 secured in hubs 1, which may form an integral part of the riser web H'. The outer truck wheels are carried by means of a yoke M, the latter being provided at its outer ends with axles 2, on which are mounted the outer wheels. The yoke M is attached to the horizontal web by means of a pin connection 75 3, the said web on its under side having lugs 4, fitting between lugs 3' on the yoke, the pins 3 engaging the lugs 4, and thus forming 85 a suitable pivotal connection between the step tread and the yoke M.

Now as before stated herein, there is provided in the present instance, but a single driving chain, the use of only a single chain being preferable to a double or two chain drive for particular reasons which I will now point out. The main objection to the employment of a two chain drive, resides in the objectionable see saw movement of the 90 steps, which results by reason of the unequal load distribution thereon. It has been found that the live load as a general rule, becomes concentrated on one side of the conveyer, thus throwing the load on only one of the 95 driving chains, and under such conditions the driving action of the two chains tends to produce a see saw movement of the steps.

In the present instance the driving chain, designated by the reference letter P, is 100 105 110

positioned on a practical center, coinciding with the center line of the conveyer.

The driving chain comprises a series of links 5, which are connected by pins 6 to form an endless chain, the same passing around a pair of sprocket wheels 7 at the upper and lower landings. Either one or both of these sprocket wheels may be driven from any suitable source of power.

10 Now in order to adapt my present type of conveyer to a single chain drive, I resort to a modified construction of certain of the parts, the most essential modification being to construct the riser to accommodate the driving chain. In the way of accomplishing this result, I provide a cut out portion such as 7' in the riser web H', as is illustrated in Figs. 2 and 4. With this construction the riser, by reason of the cut out portion, is 20 permitted to straddle the chain (see Figs. 2 and 4), thus permitting free and proper movement of the steps without interference between the riser and chain, which interference would otherwise exist, particularly 25 on the horizontal run of the steps and also as they pass around the sprocket wheels, as will be noted by reference to Figs. 1 and 2.

The front or forward end of the steps, that is relatively to the direction of movement, are pivotally connected to the driving chain, the latter, to be more specific, being attached to the yoke M of each step, by means of special pins such as 8, which are bolted to a web forming an integral part of 35 the yoke M.

In the way of preventing wear or friction between the side or lateral faces of the driving chain and ribs J forming the riser, I provide a pair of antifriction rollers 9 (see 40 Fig. 4) which are contained in such links of the chain as straddle the riser portion, these rollers projecting somewhat beyond the lateral face of the link, and bearing against the lateral face of the riser.

45 Having thus described my invention, what I claim as new and desire to secure by Letters Patent of the United States is:

1. An endless conveyer comprising a step connected to a single driving chain and having its riser adapted to straddle the chain.

2. An endless conveyer comprising a step, a yoke connected to the front end of the step, and a single driving chain connected to the yoke.

3. An endless conveyer comprising a step, a yoke connected to the front end of the step, the yoke bearing a pair of truck wheels, and a single driving chain connected to the yoke.

60 4. An endless conveyer comprising a step pivotally connected to a single driving chain, the riser of the step being constructed to accommodate the chain.

61 5. An endless conveyer comprising a step pivotally connected at one end to a single

driving chain disposed approximately on the longitudinal center line of the step.

6. An endless conveyer comprising a step having a vertically grooved riser, and a single driving chain pivotally connected to the step, the riser having a cut-out portion 70 to accommodate the chain.

7. An endless conveyer comprising a step pivotally connected at its front end to a single driving chain disposed on approximately the longitudinal center line of the 75 step, the riser having a cut-out portion to accommodate the chain.

8. In an endless conveyer, a step having a riser provided with slots adapted to register 80 with projections formed on the tread of an adjacent step, and a single driving chain pivotally connected to the front end of the step.

9. In an endless conveyer, a step formed 85 of a horizontal web for a tread, a transverse web for the riser, and a single driving chain connected to the front end of the horizontal web.

10. In an endless conveyer, a step formed 90 of a horizontal web for a tread, a transverse web for the riser, and a single endless chain connected to the front end of the horizontal web, the riser being constructed to straddle the chain.

11. In an endless conveyer, a step having 95 longitudinal grooves on its tread surface and vertical grooves in its riser in staggered relation to the grooves in said tread surface, and a single endless chain pivotally connected to the said step, the riser being constructed to straddle the chain.

12. In an endless conveyer, a step formed 100 of a horizontal web, a yoke connected to the front end of the web, and a single driving chain connected to the yoke.

13. In an endless conveyer, a step having 110 a longitudinally grooved tread surface, and a vertically grooved riser, a yoke connected to the front end of the step, and a single driving chain pivotally connected to the yoke, the riser being constructed to straddle the chain.

14. In an endless conveyer, a step provided with a pair of truck wheels at either 115 end of the step, the said truck wheels being mounted exteriorly of the tread, and a yoke supporting one pair of the truck wheels.

15. In an endless conveyer, a step provided with a pair of truck wheels at either 120 end of the step, and a transverse yoke supporting one pair of the truck wheels.

16. In an endless conveyer, a step provided with a pair of truck wheels at either 125 end of the step, and a yoke connected to the front end of the step, said yoke supporting one pair of truck wheels, and bearings forming a part of the riser, for supporting the other pair of truck wheels.

17. In an endless conveyer, a step pro- 130

vided with a pair of truck wheels at either end of the step, pins carried by the riser, for supporting one pair of truck wheels, a transverse yoke connected to the step, for supporting the other pair of truck wheels; and a single driving chain connected to the yoke.

18. In an endless conveyer, a step connected to a driving chain and having its riser 10 straddling the said chain, and means for overcoming friction between the lateral faces of the chain and riser.

19. In an endless conveyer, a step connected to a driving chain and having its 15 riser straddling the said chain, and an anti-

friction roller interposed between the lateral faces of the riser and said chain.

20. In an endless conveyer, a step connected to a driving chain and having its riser straddling the said chain, and an anti-friction roller carried by the chain and bearing against the lateral face of the riser. 20

In testimony whereof, I have signed my name to this specification in the presence of two subscribing witnesses.
